UNITED STATES PATENT OFFICE.

AMATO NICOLA SAMMARONE, OF AKRON, OHIO.

ELECTRODYNAMIC MACHINERY.

1,271,374.

Specification of Letters Patent.

Patented July 2, 1918.

Application filed January 25, 1916. Serial No. 74,247.

To all whom it may concern:

Be it known that I, AMATO N. SAMMARONE, a citizen of the United States, and a resident of Akron, in the county of Summit 5 and State of Ohio, have invented certain new and useful Improvements in Electro-dynamic Machinery, of which the following is a specification.

My invention relates to improvements in 10 electro-dynamo machines, and it consists in the combinations, constructions, and arrangements herein described and claimed.

An object of my invention is to provide 15 an economical means for constructing electro-dynamic machinery, such as direct and alternating current generators or motors, these devices being constructed largely of rolled or die pressed sheet metal, the sheets being punched or pressed and the parts generally being provided with strengthening flanges.

A further object of my invention is to 20 provide a device of the type described in which the parts which are usually made of heavy solid metal, such as the forms for 25 holding magnetic core of the armature, the saddles or base portions for supporting the machines, the boxes or bearings, the commutator bar support, the hangers for holding 30 the boxes or bearings in position, the pulleys, the brush holders, are made almost entirely of pressed and flanged sheet steel, certain of the parts, however, such as the armature core support the boxes, etc., being 35 ranged to hold the heavier metals such as cores and bearing linings.

A further object of my invention is to 40 provide a construction of the type described by means of which the various parts may be more easily assembled or taken apart.

A further object of my invention is to 45 provide devices of the type described which are relatively light in weight in comparison with their efficiency.

Other objects and advantages will appear 50 in the following specification, and the novel features of the invention will be particularly pointed out in the appended claims.

My invention is illustrated in the accom- 55 panying drawings forming part of this application, in which—

Figure 1 is a central sectional view 60 through a machine showing one embodiment of my invention.

Fig. 2 is a section at right angles to 65 Fig. 1.

Fig. 3 is an end view of the device.

Fig. 4 is a side view of one of the bearing supports and its hanger.

Fig. 5 is a section along the line 5—5 of 70 Fig. 4.

Fig. 6 is a perspective view showing one form of the base or saddle.

Fig. 7 is a perspective of the base plate.

Fig. 8 is a perspective view of the brush 75 rocking device.

Fig. 9 is a perspective view of a support for the armature core.

Fig. 10 is a sectional view showing the manner of constructing the pulley. 80

Fig. 11 is a sectional view through one of the boxes or bearings.

Fig. 12 is a sectional view showing a manner of supporting the machine.

Fig. 13 is a section on the line 13—13 of 75 Fig. 12.

Fig. 14 is a perspective view of a modified form of saddle.

Referring now to Figs. 1 and 7, I have 80 shown therein a base plate 1 which is provided with bolt openings 2 bordered by flanges 3.

Supported upon the base plate is a saddle 4 like that shown in Fig. 6, this saddle being held to the base plate by means of bolts 5.

The saddle 4 is provided with 85 stamped guide sockets 4¹ arranged to receive the flanges 3 of the base plate. At 4¹ the saddle is cut away to permit access to the bolts 7.

Carried by the saddle is a ring 6 of conducting material such as iron or 90 steel, this ring being secured to the saddle by means of bolts 7 which also secure the pole pieces 8.

Secured to the ring 6 are the hangers 9 for the boxes or bearings 10. It will be noted that these hangers are flanged 95

on both sides as shown in Fig. 5. The boxes 10 are made of pressed metal each half having any form or any number of offsets desired which can also be used in the construction of pulleys and shaft hangers for all 100

purposes, there being a portion on each side of the hanger 9 secured by welding, screws or rivets, these portions inclosing bearing pieces 11, which are held in position by means of screws 12.

The lower portion of 105 the boxing is formed into an oil chamber 13 into which an oil ring 14 dips. As will be seen from Fig. 1, I may provide a strengthening member 15 which is secured to the hangers 9, thus adding strength and stability to the bearing supports.

Disposed centrally of the device and ex-

tending through the bearings is a shaft 16. This shaft is provided with a pulley 17 whose construction may be that shown in Fig. 10 in which two sections are stamped 5 or pressed out and joined together, or one section alone will form a pulley which is entirely sufficient for some purposes.

Disposed on the shaft 16 is a sleeve 18 which is provided with a pressed keyway 19 into which a key 20 may be inserted, see Fig. 1, to key it to the shaft 16. One end of this sleeve fits into the reduced portion 21 of a commutator support 22. The latter is threaded externally at one end to receive a 15 flanged U-shaped ring 23 having dove-tail flanges arranged to crowd insulating material 24 into the dove-tailed recesses of the commutator bar 25 or parts 21 and 22 may be combined in one piece. At the opposite 20 end of the commutator support 22 it is threaded internally to receive a ring 26 which is substantially Z-shaped in cross section to force a smaller ring 27 of V-shaped cross section against the insulation 24 so as 25 to crowd the insulation into the dove-tailed recess at this end of the commutator bar, thus holding the bars securely in position.

The armature core support comprises a form 28 which is made of sheet or rolled 30 steel pressed into the form shown in Fig. 9, the adjacent edges being welded, riveted, or secured together in any suitable manner so as to make a rigid form on which the core is supported. This form is shown in Fig. 9. 35 While I have shown the same as having four radially extending portions 28 it is obvious that any number might be made to accommodate different requirements without departing from the spirit and scope of the invention.

In Fig. 14 I have shown a modified form of the saddle portion of the base. In this form instead of making the saddle in one piece as in the form shown in Fig. 6, I may make it 45 in two pieces like that shown in Fig. 14 at 51, or the two pieces could be made in one as at Fig. 6. In each instance, however, the

saddle or support for the ring 6 is preferably made of sheet or rolled pressed steel flanged in the manner shown and secured to 50 a base plate made as described.

In Fig. 8 I have shown a portion of a brush holder yoke or rocking device consisting of a body portion 30 having a single sleeve 31 pressed therefrom, said sleeve being provided with slots 32. The body portion is provided with arms 33 for supporting rods 34, see Fig. 1, which bear the brush holders proper. The sleeve 31 of the yoke is rotatably mounted on one of the bearings 10 and 55 may be adjusted thereon by unscrewing and then tightening the set screws 35 which extend through the slots 32 in the bearing.

I claim:

1. In a dynamo electric machine, a base 65 plate consisting of a flat piece of metal and having oblong rectangular bolt holes and being provided with flanges bordering the bolt holes, a saddle consisting of sheet metal bent in curved form, said saddle being provided with guide sockets arranged to fit over the said base plate flanges, said saddle being 70 slideable on said base plate, means for securing the saddle in different positions with respect to the base plate, a ring arranged to 75 rest on said saddle, and means for securing the ring to the saddle.

2. In a dynamo electric machine, a base plate consisting of a flat piece of metal and having oblong rectangular bolt holes and being provided with flanges bordering the bolt holes, a saddle consisting of sheet metal bent in curved form, said saddle being provided with guide sockets arranged to fit over the said base plate flanges, said saddle being 80 slideable on said base plate, means for securing the saddle in different positions with respect to the base plate, a ring arranged to 85 rest on said saddle, and bolts arranged to pass through the curved portion of the saddle 90 into the ring for securing the ring to the saddle, said saddle having a recessed portion for permitting access to the bolts.

AMATO NICOLA SAMMARONE.
